UNITED STATES PATENT OFFICE.

JOHN FRANCIS BRICE, OF BENSalem, PENNSYLVANIA.

INTERNAL-COMBUSTION ENGINE.

1,149,178.

Specification of Letters Patent. Patented Aug. 10, 1915.

Application filed August 2, 1913. Serial No. 782,657.

To all whom it may concern:

Be it known that I, JOHN FRANCIS BRICE, a citizen of the United States, and a resident of Bensalem, in the county of Bucks 5 and State of Pennsylvania, have invented new and useful Improvements in Internal-Combustion Engines, of which the following is a full, clear, and exact description.

The invention relates to internal combustion engines of the two-cycle type in which the explosive charge is compressed in the crank case, and its object is to provide certain new and useful improvements in this class of internal combustion engines where- 10 by regularity of operation throughout a wide range of speeds and under all variations of the throttle is obtained and the working chamber is completely scavenged of the products of combustion once in each 15 revolution.

In order to accomplish the desired result use is made of means for admitting the explosive mixture to the crank case prior to the admission of a cushion of air to the 20 transfer passage, and means for admitting the cushion of air into the cylinder for scavenging purposes ahead of the explosive mixture.

A practical embodiment of the invention 25 is represented in the accompanying drawings forming a part of this specification, in which similar characters of reference indicate corresponding parts in all the views.

Figure 1 is a central cross section of the 30 internal combustion engine provided with the improvements, the section being on the line 1—1 of Fig. 4 and the piston being in lowermost position, the piston being shown in elevation with part broken out to show 35 a passage therein; Fig. 2 is a like view of the same with the piston nearing the uppermost position; Fig. 3 is a similar view of the same with the piston in uppermost position; and Fig. 4 is a sectional plan view of 40 the same on the line 4—4 of Fig. 3.

In the cylinder A of an internal combustion engine of the two-cycle type reciprocates a piston B connected by a pitman C with the crank D of the engine shaft E extending through the closed crank case F connected with the lower end A' of the cylinder A. The upper end or working chamber A² of the cylinder A is provided with a suitable ignition device G to ignite 45 the explosive charge in the usual manner.

The lower end A' of the cylinder A is

provided with an admission port a connected by a pipe H with a source of explosive mixture supply, and this admission port a is normally closed by the piston B and is 50 uncovered when the piston B moves into uppermost position. An exhaust port b connects the working chamber A² of the cylinder A with an exhaust pipe I leading to a suitable place of discharge, and the 55 working chamber A² is also provided with a transfer port c arranged approximately opposite the exhaust port b and connected by a transfer passage J with the interior of the crank case F.

A fourth port d is arranged in the cylinder A adjacent the transfer port c, that is, 60 immediately below the same, and this transfer port d is normally closed by the piston B and is adapted to be connected with the 65 transfer port c by a passage B' formed in the side of the piston B near the lower end thereof.

The operation is as follows: When the engine is running and the piston B nears its 70 uppermost position, as shown in Fig. 2, then the port a is uncovered by the piston to allow an explosive charge to pass into the lower end A' of the cylinder A and the crank case F, and immediately after this 75 the passage B' connects the fourth port d with the transfer port c to allow fresh atmospheric air to pass by way of the said port d, passage B' and transfer port c into the transfer passage J. During the follow- 80 ing down-stroke of the piston B the transfer port c and the fourth air port d are disconnected and the admission port a is closed so that the explosive charge in the crank case F and the fresh air in the transfer 85 passage J are compressed, and when the piston B moves into lowermost position it 90 first uncovers the exhaust port b to allow the products of combustion to pass out of the working chamber A², and this move- 95 ment of the products of combustion is accelerated by the compressed air in the transfer passage J now passing into the working chamber A² on the piston B uncovering the transfer port c. It will be noticed that this 100 inrushing compressed air tends to scour the working chamber A² of the products of combustion from the previous explosion, and this air also prevents the now following 105 new charge from mixing with the outgoing 110 products of combustion. On the next following upward stroke of the piston B, ports

c and *b* are closed to compress the new charge in the working chamber *A*², and when the piston nears the end of its upward stroke the port *a* is uncovered ahead of 5 connecting the ports *d* and *c* with each other, as will be readily understood by comparison of Figs. 2 and 3, in which Fig. 2 shows the ports partly uncovered prior to connecting the air admission port *d* with the transfer port *c*. By this arrangement a double purpose is accomplished, namely, first, drawing into the crank case a charge of the explosive mixture while the piston is still under a forceful suction action and irrespective of the position of the throttle, and, 10 second, admitting air into the upper end of the transfer passage subsequent to the admission of the explosive charge into the crank case to make up for the deficiency in 15 the volume of the explosive mixture supplied to the crank case and to locate the atmospheric air in the upper portion of the transfer passage for the air to pass into the working chamber of the cylinder ahead of 20 the explosive mixture for scouring purposes 25 on the next downward stroke of the piston.

From the foregoing it will be seen that no matter how little the throttle is open the suction in the crank case begins to draw in 30 the explosive mixture prior to admitting air into the transfer passage and the amount of air subsequently supplied makes up for the deficiency in volume of explosive mixture supplied during the suction stroke of 35 the piston. By the arrangement described a very desirable flexibility is obtained whereby the engine can be throttled to any desired degree without any progressive diminution in the amount of explosive mixture 40 at each stroke.

It will be seen that as the engine's speed diminishes in response to partial closing of the throttle, the length of each time interval, wherein the suction acts only to effect an 45 intake of explosive mixture before the air

admission begins, increases progressively, and consequently the amount of explosive mixture admitted at each stroke increases progressively until the force exerted at each stroke is sufficient to maintain a uniform 50 engine speed and hence the engine is not liable to come to a standstill.

It is further understood that by the arrangement described atmospheric air is compressed and passed unmixed into the working chamber for scouring purposes ahead of the charge of the explosive mixture, and in order to successfully obtain the result it is imperative that the atmospheric air does not reach the crank case but is confined 55 within the transfer passage.

Having thus described my invention, I claim as new and desire to secure by Letters Patent:

1. The combination in an internal combustion engine, of a cylinder, a crank case in which the explosive charge is primarily compressed, a transfer passage connecting said cylinder with said crank case, and means for admitting an explosive charge to 60 the crank case prior to the admission of a cushion of air to the transfer passage.

2. The combination of a cylinder having a working chamber, a crank case in which the explosive charge is primarily compressed, a transfer passage connecting said working chamber with said crank case, means for admitting an explosive charge to the crank case prior to the admission of a cushion of air to the transfer passage, and 70 means for admitting the said cushion of air to the working chamber ahead of said explosive mixture.

In testimony whereof I have signed my name to this specification in the presence 75 of two subscribing witnesses.

JOHN FRANCIS BRICE.
